United States Patent Office.

THOMAS SLAIGHT, OF NEWARK, NEW JERSEY.

Letters Patent No. 97,127, dated November 23, 1869.

IMPROVEMENT IN PADLOCKS.

The Schedule referred to in these Letters Patent and making part of the same.

To all whom it may concern:

Be it known that I, THOMAS SLAIGHT, of Newark, in the county of Essex, and State of New Jersey, have invented a new and improved Padlock; and I do hereby declare that the following is a full, clear, and exact description of the same, reference being had to the accompanying drawings, and to the letters of reference marked thereon, making a part of this specification.

This invention relates to a new and improved padlock, of that class which is provided with rack-tumblers, or slotted tumblers, to retain the bow or shackle in a locked state and serve as a safeguard against what is commonly termed "picking."

The invention consists in a peculiar construction of a pivoted dog or bolt, and one or more tumblers, the dog or bolt and tumblers being arranged relatively with each other, and the bow or shackle, that the parts comprising the working-mechanism of the lock are reduced to the smallest possible number, and a very economical, simple, efficient, and self-locking padlock obtained.

In the accompanying sheet of drawings—

Figure 1 is an internal view of my invention, shown in a locked state.

Figure 2, an internal view of the same, shown in an unlocked state.

Figure 3, a detached perspective view, slightly enlarged, of the pivoted dog or bolt.

Figure 4, a detached section of the pivoted dog or bolt, and the tumblers, taken in the line xx , fig. 1.

Similar letters of reference indicate corresponding parts in the several figures.

To enable those skilled in the art to fully understand and construct my invention, I will proceed to describe it.

A represents the case of the padlock;

B, the bow or shackle, which works on a pin or pivot, a , at one end; and

b , the fixed arbor in the case, on which the key c is fitted and turned in unlocking the lock.

These parts, being of ordinary construction, do not require a special description.

C represents a series of tumblers, which are fitted and work on a fixed arbor, d , within the case, each tumbler having a spring, e , attached, which springs have a tendency to keep the outer ends f , of the tumblers, against the inner edge of the case A, the latter serving as a stop for the same, at the point g .

Each tumbler is provided with a slot, a^* , and the slots of the several tumblers have different positions, so that they will not coincide with each other in position when the lock is in a locked state.

D is a dog or bolt, which works freely on a fixed pin, h , within the case A.

This dog or bolt has a recess made in one side, to form a hook, i , which hook, when the bow or shackle B is in a locked state, fits in an eye in the lower part of the bow or shackle. (See fig. 1.)

One portion, j , of the dog or bolt, is considerably thicker than the other part, designated by k k' , the portion k being pendent, and projecting down sufficiently far for the bit of the key to act against, when turned, after it has passed and acted upon the tumblers C.

The portion k' has a stump, l , projecting from it at right angles with its face. These parts are clearly shown in fig. 3.

The tumblers C project over the portion k' of the dog or bolt.

The operation is as follows:

Suppose the lock to be in a locked state, as shown in fig. 1, the stump l , in this case, will be out from all the slots a^* in the tumblers C, and against the adjoining edges of the latter.

The tumblers are held in position by their springs, and the hook i , of the dog or bolt, is retained in the eye of the bow or shackle B.

In order to unlock the lock, the tumblers C require to be raised so that all of their slots a^* will be brought in line with each other. This is done by the key c , the bits of which are of varying lengths, to correspond with the varying position of the slots in the tumblers.

When the key has been turned sufficiently to effect this, it then comes in contact with the pendent part k , of the dog or bolt, and actuates the latter so that it will be turned on its pivot h , and the stump l thrown into the slots a^* , and the hook i , of the dog or bolt, thrown out from the eye of the bow or shackle, as shown in fig. 2.

In order to see clearly into the novelty of the construction and arrangement of the above-described padlock, the following peculiarities must be observed:

First, that it is not a spring-lock; that is to say, the bow or shackle is not acted upon or thrown out from the case by a spring, but that it is self-locking, or locked by simply pressing the disengaged end of the bow or shackle down upon the dog or bolt.

Second, when the hook i , of the dog or bolt, is thrown out from the eye of the bow or shackle, it stays out—it cannot easily engage itself therewith. The lock can only be locked by pressing down the bow or shackle.

Third, the parts are extremely few, consisting of the pivoted dog or bolt and the tumblers, of which

there may be one or more, but a plurality of the latter will most generally be used.

Fourth, the springs *c*, of the tumblers, are the only ones used, being all that are required.

Pivoted rack-tumblers I do not claim, for they are old and well known; neither do I claim a pivoted dog or bolt; but

I do claim as new, and desire to secure by Letters Patent—

The bolt *D*, constructed with the hook *i*, projections *j k*, stump *l*, and part *k'*, when used in connection with the ordinary shackle *B*, tumblers *C*, and spring *c*, all being constructed, arranged, and operated substantially as herein described.

THOS. SLAIGHT.
